UNITED STATES PATENT OFFICE

OTTO DE LORENZI, OF MAPLEWOOD, NEW JERSEY, ASSIGNOR TO INTERNATIONAL COMBUSTION ENGINEERING CORPORATION, OF NEW YORK, N. Y., A CORPORATION OF DELAWARE

PULVERIZED-FUEL BURNER

Application filed September 30, 1926. Serial No. 138,597.

This invention relates to burners for pulverized fuel and has particular reference to burners in which the fuel is delivered to the burner nozzle with substantially no more air than is necessary for carrying purposes, the remainder of the air necessary for combustion being admitted, preferably, at or in the immediate vicinity of the burner nozzle.

The primary object of the invention is to provide an effective control of air admitted at the burner for various rates of firing and to so dispose the air and fuel inlets into the furnace that thorough admixture and efficient combustion will result at widely varying rates of firing.

I have illustrated my invention, in preferred embodiment, in the accompanying drawings wherein:

Figure 1 is a section through my improved burner taken on the line 1—1 of Figure 2;

Figure 2 is a front elevation of the burner;

Figure 3 is a section of a modification of my invention;

Figure 4 is a rear elevation of the burner nozzle and fuel supply line; and,

Figures 5 and 6 are developed views illustrating closed and open positions, respectively, of the air admission fins of the burner shown in Figure 3.

Referring now to Figures 1 and 2 it will be seen that the burner comprises a cylindrical casing 7, shown as having two tangential air supply connections 8, although only one may be used if desired. A flanged ring 9 is embedded or bricked in the furnace wall and assists in supporting the casing 7. The burner nozzle 10 comprises two substantially truncated conical members 11 and 12, each having a flange 13 around the periphery of

its flaring end, which are bolted together with the edge 14 of an opening in the back 15 of the casing 7. The member 12 has a fuel supply pipe 16 discharging tangentially thereinto adjacent the truncated end. A clean-out plate 17 provided with an observation glass 18 is bolted to the back of the member 12.

Another truncated conical member 19 having air admission openings 20 is supported in the burner casing, at the front by the ring

21 and at the rear by the flange 22 bolted to a cylindrical seat 23 formed on the nozzle member 11 near its delivery opening 24. Air openings 25 are also provided in the shoulder 26 of the conical member 19 adjacent the delivery end of the nozzle 10. A frusto conical member 27 is positioned, and adapted to turn, around the member 19 and is provided with openings 28 which correspond with the openings 20. It is to be noted (see Fig. 1) that the openings 20 and 28 in the frusto conical members 19 and 27 are set at an angle to the radii of those members in order that the air which is admitted tangentially into the burner casing may pass into the fuel stream without material resistance and without losing its swirling motion. A ring 29 is positioned, and adapted to turn, around the flange 22 adjacent the shoulder 26 and has openings 30 corresponding with the openings 25 in the shoulder. Apertured lugs 31 and 32 are provided on the members 27 and 29 respectively for attachment of some suitable controls, as the rods 32, to the outside of the burner casing. The ring 29 is retained adjacent the shoulder 26 by the collar 33 bolted onto the seat 23 with the flange 22, the member 27 being held in its socket 34 in the ring 21 by the ring 29.

Referring now to the modification shown in Figures 3, 5 and 6, the burner nozzle 10 is the same as that shown in Figure 1. It is supported in this instance, however, by a number of brackets 36 supported on a member 37 embedded in the furnace wall. A ring 35, bolted between the two parts 11 and 12 of the burner nozzle 10, is secured to the brackets 36 by the bolts 38 thus forming a rigid support for the nozzle.

Air admission is provided through a radial set of segmental like vanes 39 which are pivoted at their inner ends, in the enlarged portion 40 of the nozzle member 11 near the delivery end thereof, and at their outer ends, at one side, in the supporting member 37. A flanged ring 41 having recesses 42 in its flange serves to space and support the pivot pins 43 at the outer ends of the vanes 39. Near the swinging edge of each vane 39 is provided a pair of apertured lugs 44 carry-

ing a pin 45 which connects the vane with the operating collar 45^a. Several operating rods 46 are secured to the collar 45 with a fork connection 47 and extend back of the brackets 36 through the ball and socket joint 48 and 49 mounted on the bracket. The rod 46 has freedom of motion through the ball 48. A set screw 50 is provided in the ball member of the joint to secure the rod 46 in position after the 10 vanes 39 have been set for a particular operating condition.

It is to be noted that the burner shown in Figure 1 has an enclosed casing and is particularly adapted for use in forced draft furnaces, whereas, the burner of Figure 3 is particularly adapted for use in furnaces where the natural draft is depended on to draw the air into the combustion chamber.

In operation, coal is admitted through the 20 supply connection 16 with substantially no more air than is necessary for carrying purposes. The location of the inlet into the nozzle member 12 and the shape of said member turns the coal away from the inlet and thus 25 reduces eddy currents and unnecessarily high air pressures in this vicinity. As a result of the angle of admission the coal is given a swirling motion and its velocity increases, as it swirls toward the delivery opening 24, to 30 about twice the admission velocity. The reduced nose portion of the delivery end of the nozzle delivers the coal into the chamber in a stream, of swirling conical configuration,

Air is admitted into the fuel stream 35 through the openings 20 and 25 (in the case of the burner of Figure 1) and through the vanes 39 (in the burner of Figure 3), which may be more or less closed according to the particular rate of firing obtaining, and it is to 40 be noted that air is admitted in both forms with a swirling motion opposite to that of the fuel stream. This results in thorough admixture of fuel and air almost before they enter the combustion space proper, and results in 45 a short and intensely hot flame.

In operating the burner of Figure 1 at very low rates of firing the openings 20 may be closed entirely and all the air may be admitted through the openings 25.

50 I claim:

1. A burner for pulverized fuel comprising a nozzle diminishing in cross section toward both ends; means for admitting fuel into one end of said nozzle, transversely and 55 at one side thereof; and a delivery opening in the other end of said nozzle.

2. A burner nozzle for pulverized fuel burners comprising two substantially truncated conical members communicating 60 through their flaring ends; a fuel inlet at one end of said nozzle disposed to deliver fuel tangentially thereinto; and a fuel delivery opening in the other end of said nozzle.

65 3. A burner nozzle for pulverized fuel burners being substantially circular in cross

section but diminishing toward each end, a fuel inlet thereto disposed at one end thereof substantially tangentially thereto, together with a delivery opening at the other end.

In testimony whereof I have hereunto 70 signed my name.

OTTO DE LORENZI.
